INVENTOR.
Sverre Quisling,

Geo. Kimmel, ATTORNEY.

UNITED STATES PATENT OFFICE.

SVERRE QUISLING, OF MADISON, WISCONSIN.

SANITARY FOLDABLE COT OR SEAT.

Application filed March 27, 1926. Serial No. 97,993.

This invention relates to a foldable sanitary support for use as a bed, cot, cushion, seat, foot and leg rest and has for its object to provide, in a manner as hereinafter referred to, a foldable support capable of being conveniently used for any one of the purposes aforesaid and including a flexible, resiliently anchored body portion to provide a sanitary, yielding and cushioned supporting means for the user.

Further objects of the invention are to provide, in a manner as hereinafter set forth, a foldable support for any one of the purposes hereinbefore referred to, and which is simple in its construction and arrangement, strong, durable, sanitary, compact when folded, readily set up in supporting position, thoroughly efficient in its use, conveniently folded, and comparatively inexpensive to manufacture.

With the foregoing and other objects in view, the invention consists of the novel construction, combination and arrangement of parts as hereinafter more specifically described, and illustrated in the accompanying drawings, wherein embodiments of the invention are shown, but it is to be understood that changes, variations and modifications can be made which will fall within the scope of the claims hereunto appended.

In the drawings wherein like reference characters denote corresponding parts throughout the several views:—

Figure 1 is a top plan view of the foldable sanitary support, in accordance with this invention.

Figure 2 is a section on line 2—2, Figure 1.

Figure 3 is a perspective view of one of the side members of the support.

Figure 4 is a transverse sectional view of a modified form of foldable support in accordance with this invention.

Figure 5 is a perspective view of one of the side members of the support employed in the form shown in Figure 4.

Figure 6 is a top plan view of a modified form of foldable support in accordance with this invention.

Figure 7 is a bottom plan view of the form shown in Figure 6.

Figure 8 is a section on line 8—8 of Figure 6.

Figure 9 is a section on line 9—9, Figure 6.

Figure 10 is a fragmentary view in trans-

verse section of the form shown in Figure 6 with the tabs of the body portion extended from each other.

Figure 11 is a perspective view of the latching member employed in the form shown in Figure 6.

Figure 12 is a top plan view of still another modified form of a foldable support in accordance with this invention.

A foldable sanitary support, in accordance with this invention, with reference to the form shown by Figures 1, 4 and 6 includes a flexible body portion provided at each side with a resilient anchor to set up a cushioning action when the body portion is used. The resilient anchors can be connected to the sides of the body portion in any suitable manner, but preferably as a continuous folded flexible body portion is employed, the resilient anchors are arranged therein and positioned against the bends of the folds of the body portion which extends lengthwise of the latter.

Referring to Figures 1, 2 and 3 of the drawings the reference character 15 generally indicates a folded flexible body portion formed from a web of any suitable material having the ends thereof indicated at 16, secured together as at 17, by suitable stitching or otherwise, so that a continuous folded flexible body portion is formed. One of the folds of the body portion is indicated at 18 and the other at 19. The bend between the folds at one side of the body portion 15 is indicated at 20 and the bend between the folds at the other side of the body portion 15 is indicated at 21.

Arranged within the body portion 16 at each side thereof is a resilient anchor 22 of any suitable construction, but preferably a pneumatic tube 23 of a length greater than the length of the body portion and of appropriate diameter. Each of the anchors 22 has its ends projected from each end of the body portion and one of the ends of each of the tubes 23 is provided with a valve controlled filling opening 24.

Associated with the body portion 15 is a pair of side members 25 consisting of an elongated plate formed with a longitudinally extending slot 26. The length of each side member corresponds substantially to the length of a resilient anchor 22 and each side member projects from each end of the body portion. The slots 26 in the side members are provided for the passage of

the folds of the body portion 15 and the side members are positioned inwardly with respect to the resilient anchors 22. The side members are fixedly supported in any suitable manner or held stationary, when the support is set up for use. When weight is applied to the body portion 15 the sides thereof tend to pass inwardly through the slots 26 in the side members, but as the resilient anchors 22 are of materially greater diameter than the slots 26, the sides of the body portion 15 are resiliently bound against the outer faces of the side members thereby providing for a cushioning action to the user of the body portion 15.

Referring to Figures 4 and 5 of the drawings the flexible body portion referred to generally by the reference character 25 is constructed in the same manner as the body portion 15 and the same type of resilient anchors, indicated at 27, as that shown in Figures 1 and 2 is employed. The anchors 27 are arranged in the body portion 25 in the same manner as the anchors 22 are arranged in the body portion 15. In Figure 1 of the drawings the folds of the body portion 15 abut, whereas in Figure 4 of the drawings, a heat resisting element 28 is interposed between the folds 29 and 30 of the body portion 25.

The structure shown in Figure 4 of the drawings, includes a different form of side members from that employed in the structure shown in Figure 1. In Figure 4 each of the side members is referred to by the reference characters 31 and consist of an inverted L-shaped bracket 32, provided with end pieces 33. The horizontal arm of the bracket 31 extends inwardly at right angles to the upper portion of the vertical arm of the bracket. The horizontal arm of the bracket 32 is formed with a lengthwise extending slot 33, through which passes the folds of the flexible body portion 25. The resilient anchors 27 are positioned within the body portion and extend over the horizontal arms of the brackets 32 whereby when pressure is applied to the body portion 25 the latter and the anchors 27 bind against the upper face of the side members 31 and set up a cushioning action to the user of the body portion 25. The vertical legs of the brackets 32, which constitute the side members 31, are detachably secured, as at 34, to a pair of opposite supports or opposed walls 35.

Referring to Figures 6 to 11 of the drawings, the side members 36 illustrated thereby, as well as the resilient anchors 37, are of the same construction and arrangement with respect to the flexible body portion 38 as that shown in Figure 1 with respect to the body portion 15. The body portion 38 is the same in construction and arrangement as the body portion 15 with this exception, that the up-

per fold 39 of the body portion 38 is formed with an oval-shaped opening 40' between the transverse center and head end of the body portion 38 and the lower fold 40 of the latter is slotted as at 41, 42, 43 and 44 transversely to provide a pair of transversely extending tabs 45, 46. The end portions 46' of the web from which the body portion 38 is set up, are not connected together their entire length for a distance between the slits 41 and 42 and between the slits 43 and 44, and by not securing together such portions of the ends of the web the free ends of the tabs 45 and 46 are provided. The free ends of the tabs 45 and 46 are provided with resilient anchors 47 which are positioned below the lower face of the body portion 38 and mounted on and common to the tabs 45, 46 is a slotted plate 48 through which said tabs extend, and said plate 48 is interposed between the resilient anchors 47 and the lower face of the fold 40, see Figure 9. Normally the lower ends of the tabs which are provided with the resilient anchors abut, as shown in Figure 9 and the said lower ends are arranged below and extend across the opening 40. When the tabs are pulled apart, to the position shown in Figure 10, a passage 48 is provided which is arranged below the opening 40 and when the passage 48 is provided, a latching member 49 is employed and positioned upon the ends of the resilient anchors 47 for the purpose of maintaining the lower portions of the tabs apart to form the passage 48. The opening 40 and passage 48 are provided for excrement purposes. When the latching member 49 is removed the weight upon the body portion 38 will cause the tabs to assume the position shown in Figure 9.

In Figure 12 of the drawings the device or support is illustrated set up with respect to the body 50 of a vehicle and is arranged between a front and rear seat 51, 52 thereof, and it consists of a pair of oppositely extending flexible members 53, 54 adapted to be detachably connected as at 55 to the doors of the vehicle body at the outer ends of said members 53, 54. The inner ends of said members 53, 54 extend through a slotted plate 56 and are provided with resilient anchors arranged below the plate 56. The form of device shown in Figure 12 can be employed to support the legs of a person or form a continuation of the seat 52 to constitute a bed.

A foldable sanitary support, in accordance with this invention, can be used as a bed, cot, cushion, seat, foot and leg rest and provides a flexible, resiliently anchored body portion to form a sanitary, yielding and cushioned supporting means for the user thereof, then furthermore with respect to the form shown in Figures 1 and 4, the body portion can be adjusted to change the position of the folds 29 and 30, that is to say when

the fold 29 becomes soiled the body portion can be adjusted so that the fold 30 can be employed as the upper fold, and it is thought the many advantages of a foldable sanitary support, in accordance with this invention, can be readily understood and although the preferred embodiments of the invention are as illustrated and described, yet it is to be understood that changes in the details of construction can be had which will fall within the scope of the invention as claimed.

What I claim is:

1. In a foldable support for the purpose referred to, a flexible body portion, resilient anchoring means carried at each side thereof, slotted side members entirely mounted on the body portion adjacent each side of the latter and coacting with said anchoring means to provide a cushioning action when the body portion is used, said body portion formed of a continuous web of fabric folded to provide an upper and a lower fold, said anchoring means arranged between the folds of and abutting against the bends between the folds, said anchoring means further arranged outwardly with respect to said side members, and said side members maintaining said body portion in enveloping position with respect to said anchoring means.
2. In a foldable support for the purpose referred to, a pair of spaced rectangular elements each provided with a lengthwise extending slot, a flexible body portion formed from a continuous web of fabric folded to provide an upper and a lower fold, said folds extending through a slot of each element, said elements positioned inwardly with respect to the bend between the folds, and a

pair of resilient anchoring devices, each of said devices arranged between the folds of said body portion and positioned between one of said elements and a bend between the folds, said elements coacting with said anchoring devices to provide a cushioning action when the body portion is used.

3. A foldable support for the purpose referred to comprising a flexible body portion formed of an upper and a lower fold, a tubular pneumatic anchoring element arranged at each side of the body portion, positioned between the folds of the latter and bearing against the bends between the folds, and slotted means mounted on the body portion inwardly of and coacting with said elements to provide a cushioning action when the body portion is used.

4. In a foldable support for the purpose referred to a flexible body portion formed of a continuous web of fabric folded to provide an upper and a lower fold and with the bends between the folds arranged at the sides of the body portion, a pair of pneumatic tubular cushioning elements arranged in spaced relation and each extending between the folds of the body portion, projecting from each end of the latter and further abutting against a bend between the folds, and a pair of slotted side members having the folds of said body portion extending therethrough, said side members arranged inwardly with respect to said elements and coacting with these latter to provide a cushioning action when the body portion is used.

In testimony whereof, I affix my signature hereto.

SVERRE QUISLING.
